UNITED STATES PATENT OFFICE

GEORGE STINSON, OF GARDNER, MASSACHUSETTS, ASSIGNOR TO HEYWOOD-WAKEFIELD COMPANY, OF BOSTON, MASSACHUSETTS, A CORPORATION OF MASSACHUSETTS

BABY CARRIAGE HOOD

Application filed January 15, 1932. Serial No. 586,848.

The present invention relates to collapsible hoods for baby carriages, which are arranged, when collapsed or lowered, to provide an entirely open carriage, and when raised or extended, to provide a shield or hood extending over a portion of the carriage body.

The principal object of the invention is to provide an improved hood arranged to extend over a substantial portion of the carriage body and which may be collapsed or lowered to provide an entirely open carriage, thereby incorporating the advantages of prior constructions in a hood which will protect a greater portion of the carriage than has heretofore been possible. Other and further objects and advantages will appear from the following detailed description taken in connection with the accompanying drawing, in which:—

Fig. 1 is a side elevation of a carriage hood embodying the invention, said hood being in raised position.

Fig. 2 is a perspective view of the hood of Fig. 1.

Fig. 3 is a side elevation of the hood of Fig. 1 in a partially lowered condition.

Fig. 4 is a view of the hood in the fully lowered position.

Fig. 5 is a plan view of a carriage with the hood mounted thereon, said hood being in lowered position.

Fig. 6 is a detail of a portion of the raising and lowering members, showing said members in locking position to maintain the hood raised over the carriage.

Like reference characters refer to like parts in the different figures.

Referring first to Figs. 1 and 5, the carriage body 1, suitably mounted on a wheeled chassis, not shown, is open at the top and provides parallel side walls 2 for supporting a hood 3 embodying the invention. The hood 3 is arranged to either extend over a substantial portion of the open body 1, as shown in Figs. 1 and 2, or to be collapsed or lowered into the position of Figs. 4 and 5, to permit the body 1 to be entirely open.

According to the invention, the hood 3 is supported by a plurality of U-shaped bows

4, 5 and 6 which are pivotally secured together by pins 7 and 8 carried by a fixed bow 10, all of said bows being adapted to fit the end of the body 1 when the hood is collapsed. The bow 10 is rigidly secured to the side walls 2 of the carriage body, the lower edge of the hood fabric being secured to this bow 10 and thereby held in position when said hood is raised. The upper and forward edges of the hood fabric are secured to a bow 11, similar in shape to the bows 4, 5 and 6, said bow 11 being slidably and pivotally secured to the side walls 2 of the carriage body 1, as will hereinafter appear. The intermediate bows 4, 5 and 6 are evenly spaced between bows 10 and 11 on the inside of the hood to support said hood in raised position, the pivotal mounting of said intermediate bows and the bow 11 permitting collapse of the hood to the position of Figs. 4 and 5.

The slidable and pivotal connection of the forward bow 11 to the carriage body which permits the hood to be stretched tight in raised position and to cover a substantial portion of the open body consists of guide members 12, forming integral extensions of the bow 10, that are secured on opposite sides of the carriage. The guide members 12 are provided with offset portions 13 formed with longitudinal slots 14 and 15 respectively, which receive studs 16 and 17 on the lower ends of the bow 11, thereby to permit sliding movement of the ends of said bow relative to the carriage, as well as pivotal movement of said bow about said studs.

The hood is held in raised position or is drawn into lowered position by toggle linkages 18 and 20 on opposite sides of the hood, and as the linkages 18 and 20 are identical, only one need be described. The linkage 18, shown clearly in Figs. 3 and 4, comprises members 21 and 22, the member 21 being pivotally mounted at one end on one arm of the bow 10, substantially midway thereof, and at the other end being pivotally mounted on a stud 23 in a connector 24. The other member 22 is pivotally mounted at one end to one arm of the forward bow 11 and the other end is rigidly secured in the connec-

tor 24. The stud 23, forming the pivotal connection for the member 21 in the connector 24 is positioned so that when the toggle is extended to the position of Fig. 6, the member 21 engages a portion of the member 22 and further downward or forward movement of the linkage 18 is prevented, the linkage in this position having moved downwardly sufficiently beyond its extended 10 or mid position to cause said linkage to be locked in the extended position, thereby to hold the hood in raised position.

With the toggle linkages extended in the position of Figs. 1 and 2, said linkages urge 15 the bow 11 forwardly at the top to tension the top portion of said hood. The linkages also tend, by reason of the location of their pivotal connections on the arms of the bow 11 to urge the ends of said bow forward in 20 the slots 14 and 15, thereby tensioning the sides of said hood and extending it forwardly over the carriage to a substantial extent. The location of the pivotal connections of 25 the toggle linkages on the end bows 10 and 11 also causes the hood to be stretched between said bows without tending to pull the hood away from the carriage around the bottom edge thereof. Furthermore, by supporting the entire hood assembly, including 30 the pivot pins 7 and 8 and the studs 16 and 17, on the lower bow 10 and the guide members 12, said hood is readily attached to or removed from the carriage body, as a unit.

In operation, the person wishing to lower 35 the hood releases the toggle joints by lifting up on handles 25 on the connectors 24, thereby raising the opposite toggle linkages to cause the hood to be collapsed to the position of Fig. 3, the bows 4, 5 and 6 pivoting about 40 the pins 7 and 8 and the bow 11 pivoting about the studs 16 and 17. In order that the hood may be fully collapsed, and that the bow 11 shall register with the other bows 4, 5, 6 and 10, in the fully collapsed position 45 of Fig. 4, to provide an entirely open top, the movement of said hood from the position of Fig. 3 involves sliding movement of the studs 16 and 17 toward the left, in the slots 14 and 15, this sliding movement 50 occurring in response to a pull to the left and downward, Fig. 3, on the handles 25 on the connectors. The hood is raised by the reverse movement of handles 25, which first partially raise the hood and slide the 55 bow 11 toward the right, to the position of Fig. 3 and then in response to further movement of said handles, causes the bows 4, 5, 6, and 11 all to pivot about their connections to permit the hood to be fully raised and locked in position.

From the foregoing, it will be apparent that the invention is embodied in a hood for baby carriages which is arranged to be readily collapsed in such a manner that 60 the entire top of the carriage body is open

and is also arranged so that when the hood is in raised position, a substantial part of the open top of the carriage body is protected by said hood. In addition, the parts entering into the invention are so assembled 70 that the hood structure may be applied to or removed from a baby carriage body, as a unit.

I claim,

1. In a hood for a baby carriage, a lower bow secured to the carriage, a plurality of intermediate hood supporting bows pivotally secured at opposite ends to the carriage, a forward bow slidably and pivotally secured at opposite ends to said carriage, and a toggle linkage between said forward bow and the lower bow to hold said bows separated and the hood in raised position. 75

2. In a hood for a baby carriage, a lower bow secured to the carriage, a plurality of intermediate hood supporting bows pivotally secured at opposite ends to the carriage, a forward bow slidably and pivotally secured to said carriage, and a toggle linkage between said forward bow and the lower bow 80 to hold said bows separated and the hood in raised position, movement of said toggle linkage being arranged to procure lowering or raising of said hood. 85

3. In a hood for a baby carriage, an upper hood supporting bow to which the forward edges of the hood are secured, a plurality of intermediate bows supporting said hood, a lower bow to which the lower edges of said hood are secured, said intermediate bows being pivotally secured to said carriage, said lower bow being rigidly secured to the carriage, and said upper bow having a slideable and pivotal connection therewith, and a folding brace between said lower and 100 said upper bows to maintain said hood in raised position and to urge said upper bow along the slide connection away from said other bows to extend said hood and to maintain said hood in extended position. 105

4. In a hood for a baby carriage, an upper hood supporting bow to which the forward edges of the hood are secured, a plurality of intermediate bows supporting said hood, a lower bow to which the lower edges 115 of said hood are secured, said intermediate bows being pivotally secured at opposite ends to opposite sides of a carriage, and said forward bow being slidably and pivotally secured at opposite ends to opposite sides of said carriage, and a toggle linkage connecting said lower and upper bows to maintain said top in raised position and said upper bow spaced from said other bows, movement of said linkage, upon release, procuring collapse of said hood, and sliding movement of said upper bow to coincide with said other bows in the collapsed position of said hood. 120

5. An attachment for a baby carriage, 125

130

comprising a hood of flexible material, a lower hood supporting bow to which the lower edges of said hood are secured, extensions rigidly secured to opposite ends of 5 said bow, a plurality of intermediate hood supporting bows pivotally secured at opposite ends to said extensions, a forward hood supporting bow pivotally and slidably secured at opposite ends to said extensions,

with the forward edges of said hood secured to said bow, and a folding brace secured to and extending between said lower bow and said forward bow to maintain said hood in open stretched position, all said bows, with the hood thereon, being attached to or removed from the carriage as a unit. 70
